UNITED STATES PATENT OFFICE.

CHARLES H. TURNER, OF WORCESTER, MASSACHUSETTS, ASSIGNOR TO OSGOOD
BRADLEY CAR COMPANY, OF WORCESTER, MASSACHUSETTS, A CORPORA-
TION OF MASSACHUSETTS.

CAR DOOR AND STEP MECHANISM.

1,164,239.

Specification of Letters Patent.

Patented Dec. 14, 1915.

Application filed January 9, 1915. Serial No. 1,424.

To all whom it may concern:

Be it known that I, CHARLES H. TURNER, a citizen of the United States, residing at Worcester, in the county of Worcester and 5 State of Massachusetts, have invented a new and useful Car Door and Step Mechanism, of which the following is a specification.

This invention relates to a car door and step mechanism and is particularly designed for 10 use in connection with side platform doors upon passenger cars. Such cars, particularly if designed for electric operation, are commonly provided with side entrance and exit platform doors and with an outside 15 step below the platform level. It is desirable that this step should be removed from operative position when the doors are closed to prevent any attempt to board the car while in motion. In some instances separate 20 steps have been provided for entrance and exit and each step has been actuated only in connection with its respective door. In other instances a single long step for both doors has been operated in connection with 25 simultaneous opening or closing of both doors. The first arrangement involves duplication of parts and also seriously limits the available step surface when one door only is open. The second arrangement places an 30 unnecessary burden upon the employee who operates the controlling mechanism, as both entrance and exit doors must be moved whenever either entrance or exit is desired, whereas in the majority of instances a single 35 door only will be actually used.

It is the principal object of my invention to provide an improved door and step mechanism so constructed that a single long step will be moved to operative position whenever 40 either the entrance or the exit door is opened and also when both doors are opened together. The step is designed to remain in operative position as long as either door is open and to be moved to inoperative position upon 45 the closing of the second door.

My invention further relates to certain devices, arrangements and combinations of parts which will be hereinafter described and more particularly pointed out in the appended claims.

A preferred form of my invention is shown in the drawings in which—

Figure 1 is a plan view of a car platform, with my improved door and step mecha-

nism applied thereto; Figs. 2 and 3 are companion views showing the entrance and exit doors in closed position with the step raised; Figs. 4 and 5 are views similar to Figs. 2 and 3 but showing the entrance door open and the step lowered; Figs. 6 and 7 are vertical sectional views taken along the lines 6—6 in Fig. 3, and 7—7 in Fig. 5 respectively, and Fig. 8 is an elevation of the conductor's dividing rail, with the door-operating handles and connections. 65

Referring to the drawings, 10 indicates the car body having a platform 11 adjacent thereto, provided with entrance and exit doors 12 and 13. The doors 12 and 13 are shown as formed of two panels or sections each and are arranged to fold outwardly when opened, as indicated in dotted lines in Fig. 1. The door 12 is pivoted upon an upright shaft 14 extending longitudinally both above and below the door. The door 13 is similarly pivoted upon an upright shaft 15.

The car step 16 is mounted upon arms 17—17^a. (Figs. 1, 6 and 7) pivoted at 18 to brackets 19 fixed to the under-frame of the car platform. The car step is connected for operation simultaneously with either door by the following mechanism: The arm 17^a (Figs. 6 and 7) has a rearwardly and downwardly extending projection 20 to which a link 21 is pivoted by a horizontally extending stud or bolt 22. At its opposite end the link 21 is connected to a second link 23 by a vertically extending bolt 24. The opposite end of the link 23 is connected by a horizontal bolt 25 to an ear 26 upon the side of a collar 27 which is pivotally mounted upon a vertical stud 28 fixed in an arm 29 forming one part of a bell crank 30 which is pivoted upon a fixed stud 31. The links 21 and 23 and the collar 27 constitute a universal connection between the arm 17^a and its bell-crank 30. A second arm 32 (Figs. 3 and 5) of the bell-crank 30 is pivotally connected to a casting 33 having a sleeve 34 secured thereto or integral therewith. A plunger 35 is freely slideable in the sleeve 34 and is secured to a casting 36 which is pivoted in turn on an arm 37 which is fast upon the lower end of the shaft 15. A similar set of 100 connections are provided between the step supporting casting 17 and the lower end of the shaft 14 which supports the door 12. 95

105

Heavy coil springs 38—38 (Figs. 4 and 5) are mounted upon a rod 18 which constitutes the pivot for the step 16, one end of each spring being extended as indicated at 39 to engage the lower side of the step while the opposite end is similarly extended and engages a fixed part of the platform frame. The tension of the spring is so disposed that the springs normally act to swing the step upward to closed position. With this arrangement of parts, the swinging of the door 12 outwardly to its open position will force the plunger 35 into the sleeve 34 until it engages the casting 33. The parts 33, 34 and 35 thereafter constitute a rigid link, transmitting motion from the arm 37 on the shaft 14 to the arm 32 of the bell-crank 30. The resulting movement of the bell-crank 30 is transmitted through the arm 29 and 20 the universal connections to the downward extension 20 of the step-supporting arm 17, moving the step to its lowered position against the tension of the springs 38. The sleeve 34 connected to the arm 17^a at the opposite end of the step must necessarily move in a corresponding manner, but the plunger 35 being fixed to the arm 37 upon the shaft 15 remains stationary. This condition necessitates relative movement between the 30 sleeve 34 and the plunger 35 which is permitted by the slidable connection between these parts. Should the door 13 be thereafter opened, its plunger 35 will be moved freely along its sleeve 34 and will contact with the end of the sleeve as the door reaches its open position.

The closing of either door while the other remains open will merely slide the corresponding plunger outwardly in its sleeve, 40 while the closing of the second door after one door has been closed will permit the springs 38 to move the step to inoperative position.

The mechanism for moving the doors themselves to open and closed position constitutes no part of my invention and any suitable devices may be utilized therefor. One form of such mechanism is shown in the drawings, in which the operating devices are disposed under the car roof, above the doors. Arms 40 and 40^a are secured to the upper ends of shafts 14 and 15 respectively and are connected by rods 41 and 41^a and castings 42 and 42^a to arms 43 and 43^a (Fig. 8) mounted respectively upon an operating shaft 44 and an operating sleeve 45. At its upper end the shaft 44 has a bearing in a bracket (not shown) secured to the roof frame and at its lower end a bearing 60 is provided in a fitting 47 forming part of a U-shaped rail 48 supported upon the car platform or upon the end of the car body.

A handle 49 is detachably connected to a collar 50 secured to the shaft 44 above the fitting 47 and constitutes means for turn-

ing the shaft 44 and thereby operating the entrance door 12. The sleeve 45 is positioned by the shaft 44 and is provided with a collar 51 and a detachable handle 52 by which the exit door 13 may be operated. With these connections, it will be seen that either door may be opened or closed independently, and that whenever either of the doors is open the step will be in operative position, while upon the closing of the second door the step will be raised. The mechanism above described is particularly designed for operation by the conductor, the U-shaped rail 48 defining the conductor's station.

Precisely similar mechanism may be provided for the doors and step upon the opposite side of the car, for use by the motorman when the car is running in the opposite direction. The only difference in the mechanism resides in the different location of the operating handles and the parts associated therewith. For the use of the motorman I provide a shaft 60 and a sleeve concentric therewith, both provided with operating handles at their lower ends and having arms at their upper ends connected by rods 61 and 62 to the arms 63 and 64 upon the door supporting shafts 65 and 66.

Having thus described my invention, it will be evident that many changes and modifications can be made therein by those skilled in the art without departing from the spirit and scope thereof as set forth in the claims and I do not wish to be otherwise limited to the details herein disclosed but

What I do claim is:—

1. In a passenger car in combination, a platform, separate entrance and exit side doors for said platform, a movable step, means to operate each side door independently, and connections from said means to said step, each connection including an extensible member effective under certain conditions to move the step positively to operative position and also under different conditions to permit movement of the step while the door associated with the connection remains closed.

2. In a passenger car in combination, a platform, separate entrance and exit side doors for said platform, a movable step, a separate set of operating devices for each door, and separate connections from each set to the movable step, each connection including a freely extensible member of fixed minimum length effective to move the step positively to operative position when actuated by its operating device, and to permit actuation of said step by the other set of operating devices, during which latter actuation said member is freely extended longitudinally.

3. In a passenger car in combination, a platform, separate entrance and exit side

doors for said platform, a movable step, a spring for moving said step to inoperative position, a separate set of operating devices for each door, and connections from said 5 devices to said step effective to permit movement of said step to operative position by either set of operating devices independently of the other set of operating devices.

4. In a passenger car in combination, a 10 platform, separate entrance and exit side doors for said platform, a movable step, a spring for moving said step to inoperative position, a separate set of operating devices for each door, and connections from said 15 devices to said step, said connections being freely extensible but of fixed minimum length and including a sleeve and a plunger freely slidable outwardly along said sleeve.

5. In a passenger car in combination, a 20 platform, separate entrance and exit side doors for said platform, a movable step, a rod upon which said step is pivoted, spiral springs encircling said rod and adapted to move said step to raised position an upright 25 operating shaft for each door, extending

downward below the platform manually operated means for moving said shaft, an arm on the lower end of each shaft, a plunger pivoted to each arm, a sleeve slidable on each plunger, and universal connections 30 from each sleeve to said step.

6. In a passenger car in combination, a platform, separate entrance and exit side doors for said platform, a movable step, means to move said step to inoperative position, separate operating devices for each door and separate connections from said devices to said step, effective to position said step for use when either or both doors are open, and to permit said step to be moved 35 to inoperative position when both doors are closed.

In testimony whereof I have hereunto set my hand, in the presence of two subscribing witnesses.

CHARLES H. TURNER.
